DESIGN FOR A BALANCING TOY

Sydney F. Gilham, Lakewood, Ohio

Application February 11, 1947, Serial No. 136,829

Term of patent 3½ years

(Cl. D34—15)

To all whom it may concern:

Be it known that I, Sydney F. Gilham, a subject of the King of Great Britain, residing at Lakewood, in the county of Cuyahoga and State of Ohio, have invented a new, original and ornamental Design for a Balancing Toy, of which the following is a specification, reference being had to the accompanying drawing, forming part thereof.

The figure is a perspective view of a balancing toy, showing my new design.

I claim:

The ornamental design for a balancing toy, as shown.

SYDNEY F. GILHAM.
